Inventor,

Morton E. Converse

By his Attorney, J. S. Brown.

UNITED STATES PATENT OFFICE.

MORTON E. CONVERSE, OF WINCHENDON, MASSACHUSETTS.

CLAMP.

SPECIFICATION forming part of Letters Patent No. 350,579, dated October 12, 1886.

Application filed February 26, 1886. Serial No. 193,526. (No model.)

To all whom it may concern:

Be it known that I, MORTON E. CONVERSE, of Winchendon, in the county of Worcester and State of Massachusetts, have invented an Improved Clamp for Gluing Boxes and Similar Articles; and I do hereby declare that the following is a full and exact description of the same, reference being had to the accompanying drawings, making part of this specification.

10 Figure 1 of the drawings represents a top view of a clamp in which to glue rectangular boxes constructed with my improvements; Fig. 2, a front view of the same; Fig. 3, a left-hand end view thereof; Fig. 4, a vertical section of the same in a plane indicated by the line 1 1, Fig. 1; Fig. 5, a top view of the clamp with a box clamped therein; Fig. 6, a front view of the same.

Like letters designate corresponding parts 20 in all of the figures.

The following parts compose the complete clamp: A is the base or body of the clamp, on which the other parts are mounted, and may be a simple rectangular piece of board. B is 25 a stationary holder, against which one side of the box X is placed for clamping the same. C is a stationary holder, against which one end of the box bears when clamped. D is a yielding or movable spring-holder, which presses 30 against the other side of the box when clamped, and E is another yielding or spring holder, which presses against the outer end of the box when clamped. One stationary holder, preferably the side holder, B, is made of considerable length, in order to hold the box firmly 35 in its position and keep it from swinging around. Of course, two or more such stationary holders in line might be used; but the single long holder answers the purpose perfectly.

40 The other stationary holder, C, may be ordinarily a simple round pin, as shown, projecting up from the base, particularly for clamping small boxes, for which the invention is specially adapted; or two or more pins might 45 be used. The two spring-holders D E may also be simple spring-wires, as represented. The spring-holders, when made of wires, as shown, may be held by screws *a a* and stay-pins *b b*. The inner faces or sides of the hold- 50 ers, preferably, are inclined a little backward from bottom to top, to facilitate the insertion

of the boxes between them, and to produce a wedging and compressing action on the sides and ends of the boxes, and thus bring their glued surfaces close together and make good 55 joints. If it is desired to glue boxes of different sizes in the same clamps, three of the holders may be adjustable in position. It is, of course, unnecessary to adjust the main holder B in any case.

60 One of the main improvements in this clamp consists in a metallic covering, *c*, for the upper surface of the base A, and of the front side or any part thereof subject to be smeared by the liquid glue, and a similar covering, *d*, for the inner and top surfaces of the guide-holder B, or such surfaces thereof as are subject to be smeared with glue, those parts being ordinarily made of wood. The purpose of this metallic covering is to prevent the glue from sticking 65 to the clamp and to enable it to be readily removed, if any should be left thereon. Simple sheet-zinc or tin-plate is very suitable for this covering, being simply nailed to the wood, or otherwise attached in an easy and inexpensive 70 way. The wire holders, being made of metal, need no such protection.

75 These clamps are inexpensive, being made of cheap material and quickly constructed.

The box is inserted in the clamp, which holds 80 the joints close until the glue is sufficiently set to make the contiguous parts adhere together, which ordinarily takes place within about five minutes after the box is placed in the clamp.

85 The method or principle of clamping is applied in whatever manner the parts of the box may be combined or united.

90 With a sufficient number of these clamps—say fifty—boxes may be held till the glue is set as fast as two attendants can insert and remove the same.

I claim as my invention—

95 1. In a gluing-clamp, the combination of the base A, covered with sheet metal, the guide-holder B, faced with sheet metal, the fixed end holder, C, and the counter spring-holders D E, placed, respectively, opposite to the holders B C, and pressing in directions at right angles to each other, whereby pressure is produced upon all sides of the box, substantially as and for the purpose herein specified.

100 2. The combination of the base A, long sta-

tionary guide-holder B, against which one side of each article glued is placed, stationary holder C, against which an end or side of the article adjacent to the first or guide side is placed, and counter spring-holders D E, respectively opposite to the holders B C, and bearing against the remaining sides of the article, substantially as herein set forth.

3. The combination of the base A, long stationary guide-holder B, rounded or sloped on its face, against which one side of the article glued is placed, stationary holder C, against which an end or side of the article adjacent to

the first or guide side is placed, and counter spring-holders D E, having outwardly and upwardly inclined bearing parts, located, respectively, opposite to the holders B C, and bearing against the remaining sides of the article, substantially as and for the purpose herein specified.

In testimony whereof I have hereunto affixed my signature in the presence of two witnesses.

MORTON E. CONVERSE.
